US0D1040622S

(12) **United States Design Patent** (10) Patent No.: **US D1,040,622 S**
(45) Date of Patent: ** Sep. 3, 2024

(54) **BREAD SLICER**

(71) Applicant: **Shenzhen Tuanxin Intelligent Technology Co., Ltd.**, Shenzhen (CN)

(72) Inventor: **Yindi Yu**, Shangrao (CN)

(73) Assignee: **Shenzhen Tuanxin Intelligent Technology Co., Ltd.**, Shenzhen (CN)

(**) Term: **15 Years**

(21) Appl. No.: **29/929,079**

(22) Filed: **Feb. 20, 2024**

(51) LOC (14) Cl. **07-04**

(52) U.S. Cl. **D7/673**
USPC ....

(57) **CLAIM**

The ornamental design for a bread slicer, as shown and described.

DESCRIPTION

FIG. 1 is a top perspective view of a bread slicer, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is its split state diagram.

The broken lines in the drawings illustrate the portions of the bread slicer, which form no part of the claimed design.

1 Claim, 9 Drawing Sheets
